United States Patent Office

Des. 205,090
Patented June 21, 1966

205,090

BEADING TOOL

James M. Sexauer, Harrison, N.Y., assignor to J. A. Sexauer Mfg. Co. Inc., New York, N.Y., a corporation of New York

Filed Sept. 21, 1965, Ser. No. 87,098

Term of patent 14 years

(Cl. D54—13)

FIG. 1 is a plan view of one side of a beading tool, showing my new design;

FIG. 2 is a side view thereof;

FIG. 3 is an end view thereof; and

FIG. 4 is a plan view of the other side thereof.

I claim:

The ornamental design for a beading tool, substantially as shown.
